UNITED STATES PATENT OFFICE.

ARTHUR WINDING, OF WAUWATOSA, WISCONSIN.

ROOFING.

Application filed December 8, 1922. Serial No. 605,584.

To all whom it may concern:

Be it known that I, ARTHUR WINDING, a citizen of the United States, residing at the town of Wauwatosa, in the county of 5 Milwaukee and State of Wisconsin, have invented certain new and useful Improvements in Roofings, of which the following is a specification, reference being had to the accompanying drawing, forming a part 10 thereof.

This invention relates more particularly to roofing made in factories ready for laying and consisting of continuous or long flexible waterproof sheets of fibrous material 15 such as the so-called roofing felt, or asbestos roofing, and laid with lapped joints.

The main objects of the invention are to avoid exposed straight or continuous edges 20 on the overlapping parts of the sheets, which tend when laid and nailed in the ordinary way, to buckle, wrinkle or curl, on account of unequal expansion and contraction due to variations in temperature and humidity, and to spring away from the underlying sheets, 25 so that wind, rain or water can get between the sheets and lift and separate the overlapping edges from the underlying sheets thereby causing disintegration of the pitch coating between them, and leaking and rapid de- 30 struction or deterioration of the roofing; to avoid the use of exposed nailing strips or nails for fastening the overlapping edges of the sheets in place; and generally to im- 35 prove the construction and facilitate the laying of prepared roofing of this class.

It consists in the construction and method 40 of laying the roofing sheets and in the arrangement and combination of parts of the roofing as hereinafter particularly described and pointed out in the claims.

In the accompanying drawing like characters designate the same parts in the several figures.

Figure 1 is a plan view of a limited portion 45 of roofing comprising parts of lapping sheets constructed and laid in accordance with the invention; Fig. 2 is a section on the line 2—2, Fig. 1; Fig. 3 is a similar section of the serrate and perforated overlapping edge of a sheet before it is laid and cemented to an adjoining sheet; Fig. 4 is a plan view similar to Fig. 1 of a modification 50 of the roofing; and Fig. 5 is a section on the line 5—5, Fig. 4.

Referring to Figs. 1, 2 and 3, one prac-

tical embodiment of the roofing comprises flexible waterproof sheets 1, of fibrous material such as the so-called prepared roofing felt or asbestos roofing. The sheets are laid in accordance with the usual practice in laying such roofing, beginning with one side 60 of a roof, usually the lower side when the roof is inclined, and progressing towards the higher or other side of the roof, each succeeding sheet being lapped over the preceding sheet.

To the lapped portion of each preceding sheet a heavy coating 3, of pitch such as asphalt, coal tar or the like, is applied before the next sheet is laid. The overlapping 70 portion of each succeeding sheet is formed with a serrate or zigzag edge 4, and to further insure a secure bonding or attachment of the overlapping part of the sheet to the underlying sheet, may be formed adjacent 75 the serrate or zigzag edge, with holes or perforations 6, of any suitable shape or size, preferably arranged in a series parallel with the longitudinal edges of the sheet and suitably spaced from one another.

The overlapping parts of the sheets as they are successively laid, are pressed into and embedded in the coatings 3 of pitch by which the lapping portions of the sheets are cemented to each other and the joints between the serrate edges of the overlapping parts of the sheets and the underlying parts of adjoining sheets are covered, protected and sealed against the entrance of wind, air, 85 rain or water between the sheets. The dis- 90 integration or deterioration of the pitch coating between the sheets and consequent detachment and separation of the lapped portions of the sheets from one another are thus prevented.

The soft or plastic pitch in which the overlapping parts of the sheets are embedded, is displaced and pressed outwardly and upwardly around the serrate edges 4 of the sheets and into the spaces between the 100 underlying edges 5 and the overlying portions of adjoining sheets, as shown in Fig. 2.

When the sheets are perforated adjacent their serrate edges, as shown in Fig. 3, the soft or plastic pitch is pressed upwardly and 105 fills the holes or perforations 6, preferably till it overflows the edges of the holes or perforations, as shown in Figs. 1 and 2, thereby forming bonds or additional fastenings 7 between the sheets, the bonds when 110

they overflow the edges of the holes being clenched over the upper exposed faces of the sheets.

When the roofing is laid, as shown in Figs. 5 and 2, on a cement, concrete, tile or similar foundation 8, having no joints, cracks or openings through which the pitch when softened by hot weather can run, a coating 9 of pitch, is applied to the entire surface 10 of the foundation, and the coatings 3 between the lapped portions of the sheets extending beyond adjacent edges of adjoining sheets, coalesce and unite with the coating 9 adjacent the underlapping edges 5. The 15 lapped portions of the sheets are thus cemented and secured together, and the roofing cemented and secured to the foundation 8 by the pitch coatings; nailing strips or nails for fastening the lapped portions 20 of the sheets together and the roofing to the foundation, are entirely dispensed with, and the labor and trouble of nailing, the warping or buckling of the sheets and leakage incident to the use of nails, are avoided. 25 The lapped portions of the sheets are permitted by the semi-fluid and elastic properties of the pitch, to shift slightly upon one another and upon the foundation under varying conditions of temperature and humidity, thereby tending to avoid buckling, warping and separation of the sheets from one another and from the foundation.

When the roofing is laid as shown in Figs. 4 and 5, on a board, wood or other foundation 8', having joints, cracks or openings through which fluid or softened pitch could run, the continuous coating 9 of pitch used on a cement, concrete, tile or similar roof foundation is omitted, and the coatings 3 between the lapped portions of the sheets are kept out of contact with the foundation. This may be accomplished by applying the coatings 3 so that they will terminate some distance from the underlying edges 5 of the sheets, or preferably, as shown, by flexible extension strips 10 of roofing material lapped underneath and extending beyond the overlapped edges 5 of the sheets 1, and fastened therewith at intervals by nails 11 to the foundation 8'. The coatings 3 of pitch are then spread completely over the underlapping portions of the sheets 1, covering the nail heads and adjacent portions of the upper sides of the strips 10, but terminating a distance from the then exposed edges 5 of the strips which are subsequently covered by successively laid sheets.

To insure covering, protecting and effectively sealing the overlapping serrate or zigzag edges 4 of the sheets and preventing the entrance of wind, air, rain or water between the lapped portions of the sheets, extra coatings 12 of pitch may be applied to the overlapping parts of adjoining sheets, as shown in Figs. 4 and 5, such coatings ex-

tending over and coalescing and uniting with the coatings 3 between the sheets along the serrate or zigzag edges thereof.

When the sheets are perforated as shown, these outer coatings 12 extend over the holes 70 or perforations 6 and coalesce with the bonds 7, thus reinforcing and increasing the effectiveness of the bonds and of the pitch coatings 3 between the sheets to secure the lapping portions of adjoining sheets to each 75 other and exclude air and water from the joints between them.

I claim:

1. A flexible waterproof roofing sheet of fibrous material having a serrate edge and 80 holes adjacent the serrate edge for overlapping, bonding and sealing it with pitch to an underlying sheet.

2. Roofing comprising lapped waterproof sheets, one sheet having a serrate edge overlapping and cemented to an underlying sheet 85 by a coating of pitch in which the overlapping serrate edge is embedded and sealed.

3. Roofing comprising lapped waterproof sheets having serrate edges and perforations 90 overlapping adjoining sheets and cemented thereto by pitch in which the serrate edges of the sheets are embedded and sealed, the pitch being pressed upward into the perforations and forming bonds between the 95 lapped portions of the sheets at a distance from the overlapping serrate edges.

4. Roofing comprising lapped flexible sheets having serrate edges overlapping adjoining sheets and cemented thereto by coatings of pitch in which the serrate edges are embedded and sealed and an extra coating of pitch applied to the upper sides of the overlapping portions of the sheets and coalescing along the serrate edges of the sheets 100 with the coatings between adjoining sheets.

5. Roofing comprising lapped flexible sheets having serrate edges and perforations adjacent the serrate edges, the lapped portions of adjoining sheets being cemented 110 and secured together by coatings of pitch in which the overlapping serrate edges are embedded and sealed and which are pressed upwardly into such perforations to form bonds, and extra coatings of pitch applied 115 to the overlapping parts of adjoining sheets and coalescing with the coatings between the sheets along the overlapping serrate edges and with the bonds in the perforations.

6. Roofing comprising lapped flexible sheets having serrate overlapping edges, flexible extension strips lapped under and nailed with the underlying edges of adjoining sheets to the roof foundation and extending beyond the underlying edges of the sheets, and coatings of pitch spread over the underlapping portions of the sheets and adjacent portions of the extension strips, partially covering the extension strips and ce- 130

menting and securing the overlapping to the underlying portions of the sheets, the overlapping serrate edges of the sheets being embedded in and sealed by the pitch coatings.

7. A flexible, waterproof sheet provided with a serrate edge to prevent the buckling, wrinkling, or curling of the edge of the sheet as a whole, said serrate edge being adapted to be cemented to an underlying member at the plurality of the separate edges of the serrate edge, holes being provided in said

sheet to provide edges for cementing the sheet at separated points to an underlying member.

8. In a roof construction, a plurality of overlapping strips of roofing material having their exposed edges serrated, and a bonding material applied to the adjacent surfaces of said strips at said edges.

In witness whereof I hereto affix my signature.

ARTHUR WINDING.
